CLAIM

The ornamental design for a package for human and pet food, as shown and described.

DESCRIPTION

FIG. 1 is an elevated perspective view of the package for human and pet food showing our new design;
FIG. 2 is a left side view, the right view being a mirror image thereof;
FIG. 3 is a top view thereof;
FIG. 4 is a bottom view thereof; and,
FIG. 5 is a front view thereof.
